United States Patent Office

Des. 179,637

Patented Feb. 5, 1957

179,637

ELECTROMAGNETIC UNIT

Hugh J. Hall, Los Altos, Ralph W. Kane, Atherton, and
Emery H. Rogers, Palo Alto, Calif., assignors to Varian
Associates, San Carlos, Calif., a corporation of Cali-
fornia

Application January 24, 1955, Serial No. 34,183

Term of patent 14 years

(Cl. D26—5)

FIG. 1

Fig. 1 is a front perspective view of an electromagnetic unit showing our new design;

Fig. 2 is a view in front elevation; and

Fig. 3 is a view in side elevation.
The rear of the electromagnetic unit, not shown, is substantially like the front thereof.

We claim:

The ornamental design for an electromagnetic unit, as shown and described.
